Attest,

UNITED STATES PATENT OFFICE.

IRWIN P. DILLON, OF LAWRENCE, MASSACHUSETTS, ASSIGNOR OF ONE-HALF TO HENRY C. KING, OF SAME PLACE.

DESIGN FOR A BEATER-TROUGH PLATE FOR PAPER MANUFACTURE.

SPECIFICATION forming part of Design No. 32,169, dated January 30, 1900.

Application filed December 21, 1899. Serial No. 741,193. Term of patent 14 years.

To all whom it may concern:

Be it known that I, IRWIN P. DILLON, a citizen of the United States, residing at Lawrence, in the county of Essex and State of Massachusetts, have invented and produced a certain new and original Design for a Beater-Trough Plate for Paper Manufacture, of which the following is a specification, reference being had to the accompanying drawings, forming 10 a part thereof.

In the drawings, Figure 1 represents my design in perspective, and Fig. 2 is a perspective view thereof viewed from the opposite end.

The leading or material feature of my design for a beater-trough plate consists of a 15 hollowed or sloping trough having a high and narrow portion at one end a , the trough growing deeper and wider throughout its length toward the opposite end or side of the plate 20 at a' , the rear wall or surface a^2 of the trough being curved downwardly and inwardly along the back part of the trough, the front wall having a level straight top extending approximately half the length of the trough and the 25 rear wall having a curved top sweeping in an

eccentric curve from the outer end of said front wall to approximately opposite the inner end of said front wall

As shown, the front wall a^3 of the trough has its top edge a^4 horizontal, and the rear wall a^2 extends back from the right-hand end of the said top edge a^4 in an irregular curve and forwardly with a wide sweep, terminating at a^{10} opposite the wall a^3 , so that the trough extends from its narrow end at the junction 35 of the said rear wall and front wall, with an expanding and approximately convolute sweep partially about said front wall.

Having fully described my design, what I claim is—

The design for a beater-trough plate substantially as herein shown and described.

In testimony whereof I have signed my name to this specification in the presence of two subscribing witnesses.

IRWIN P. DILLON.

Witnesses:

GEO. H. MAXWELL,
JOHN C. EDWARDS.
